UNITED STATES PATENT OFFICE.

THOMAS P. ANTHONY, OF EDGEWATER PARK, NEW JERSEY, ASSIGNOR TO UNITED STATES CAST IRON PIPE & FOUNDRY COMPANY, OF BURLINGTON, NEW JERSEY, A CORPORATION OF NEW JERSEY.

GRINDING AND POLISHING MACHINE.

Application filed January 3, 1924. Serial No. 684,114.

To all whom it may concern:

Be it known that I, THOMAS P. ANTHONY, a citizen of the United States of America, and resident of Edgewater Park, county of Burlington, State of New Jersey, have invented a certain new and useful Improvement in Grinding and Polishing Machines, of which the following is a true and exact description, reference being had to the accompanying drawings, which form a part thereof.

My invention relates to grinding and polishing machinery and has for its object to provide a machine especially designed and adapted for the grinding and polishing of spherical pipe sockets such as are used in coupling pipes together with freedom for angular adjustment with respect to each other.

20 The nature of my improvements will be best understood as described in connection with the drawings in which they are illustrated and in which—

25 Figure 1 is a plan view of my improved machine with a spherically socketed pipe shown in place thereon and partly in section.

Figure 2 is a front elevation of my machine also showing the pipe partly in section.

30 Figure 3 is an end elevation of my machine taken from the right hand side of Figs. 1 and 2, but with a motor for driving the polishing wheel omitted.

Figure 4 is a sectional view on the line 35 4—4 of Fig. 1, and

Figure 5, a plan view of the plate J which in the construction illustrated separates the motor and polishing machine.

40 A, A, are grooved supporting wheels on which rests the socket end of the pipe. B, B, are supporting wheels on which the rear end of the pipe rests. A' and A² are the shafts which support the wheels A, A, and to which are secured the sprocket wheels A³ and A⁴ connected by the chain A⁵. A⁶ is a worm wheel secured to the shaft A², and engaged by the worm A⁷ driven by the pulley A⁸ which in turn is driven by the belt A⁹ passing over the pulley A¹⁰ driven by the motor A¹¹. C is the pipe having a spherical socket indicated at C'. D is the base frame of the machine which supports the shafts of the

grooved wheels A, A, and is formed with an upwardly extending standard D' from which extend a pivot pin E and another upwardly extending standard indicated at D² into the top of which screws the bolt indicated at E'. F is the main frame of the machine which is pivotally supported on the pin E of the standard D' and the opposite end of which rests, when the main frame is in operative position, on the standard D² which is formed with a slot F' to give passage to the clamping bolt E'. This main frame is formed with an offset boss F² and provided with a pivot pin H so located that when the frame is in operative position the pivot pin will coincide approximately with a diametric line of the socket C' and preferably, as shown, with a vertical diametric line. The frame F is also formed with a forward extension F³ and has secured to it a segmental rack, indicated at F⁴. G is a second frame pivotally supported on the pivot H and frame F, as indicated at G', and formed with a rib G³ which rests upon the frame F. This frame supports a pivot pin indicated at G² and the second pin indicated at G⁴, the function of which will be described. J is a plate supported on the frame G preferably by ball bearings, as indicated at J', and pivoted on the said frame G by the pivot pin G² passing through the pivot hole J¹, indicated in Fig. 5. J³ is a larger hole through which passes the pulley or pin G⁴, 85 the hole J³ being of such diameter as to permit of necessary angular movement of the plate on the pivot G⁴. I is a shaft secured on the underside of the frame G carrying a worm I' which is engaged in the segmental rack I⁴ and is actuated by the hand wheel indicated at I². J² is a lever arm extending out from the outer end of the plate J and to which is attached a cord K passing over a pulley K' and carrying a weight indicated at K². L is a motor carried on the outer end of the plate J having a shaft indicated at L', on the end of which is attached a polishing wheel indicated at L².

100 In the special and preferred form of construction illustrated in the drawings the pipe is supported and rotated by the supporting mechanism described and the frame F is securely clamped in operative position by

- means of the pulley E' and in this position the pivot pin H carried by this frame lies approximately in a vertical diametric line of the socket C'. The polishing wheel L² is held in contact with the vertical socket by the action of the weight K² which tends to swing the plate J in a direction to press the polishing wheel against the work. By means of the segmental rack F⁴ and worm I' the frame G is angularly adjusted on the pivot pin H so as to carry the polishing wheel over the surface of the vertical socket C' and when the socket has been completely polished the clamping bolt F' is loosened and the frame F rotated outward on its pivot E so as to remove the polishing wheel, and all parts of its supporting and actuating mechanism, from the mouth of the pipe and permit its free removal.
- Having now described my invention, what I claim as new and desire to secure by Letters Patent, is:
1. A grinding and polishing machine having in combination means for supporting and rotating a pipe having a spherical socket at its end, a main frame carrying a pivot located to lie normally in an approximate diametric line of the spherical pipe socket,

when a pipe is in position to be ground, a second frame pivoted on the main frame pivot, means for angularly adjusting said second frame, a polishing wheel supported on said second frame in position to contact with the spherical pipe socket and means for pressing said polishing wheel against the pipe socket.

2. A grinding and polishing machine having in combination means for supporting and rotating a pipe having a spherical socket at its end, a main supporting frame pivoted at a point lying beyond the pipe end when the pipe is in position to be ground and carrying a pivot located so as to lie in the vertical diameter of the spherical pipe socket when the frame is in operative position, a second frame pivotally supported on the main frame, means for angularly adjusting the second frame on the main frame, a plate pivotally supported on the second frame, a polishing wheel and means for rotating it supported on said pivoted plate and means acting on said pivoted plate to press the polishing wheel against the socket of the pipe.

THOMAS P. ANTHONY.
